CLAIM

The ornamental design for a brush holder, as shown and described.

DESCRIPTION

FIG. 1 is a top, front, right side view of a brush holder showing our new design in its assembled configuration; FIG. 2 is a front elevational view of the assembled configuration;

FIG. 3 is a left side view of the assembled configuration, the rear elevational view being a mirror image thereof;

FIG. 4 is a top plan view of the assembled configuration;

FIG. 5 is a bottom plan view of the assembled configuration;

FIG. 6 is a top, right side perspective exploded view showing the separated base and cover portions of our brush holder;

FIG. 7 is a front elevational view of the cover portion;

FIG. 8 is a left side elevational view of the cover portion, the rear elevational view being a mirror image thereof;

FIG. 9 is a top plan view of the cover portion;

FIG. 10 is a bottom plan view of the cover portion;

FIG. 11 is a top perspective view of the base portion;

FIG. 12 is a front elevational view of the base portion;

FIG. 13 is a left side view of the base portion, the rear elevational view being identical thereto;

FIG. 14 is a top plan view of the base portion; and,

FIG. 15 is a bottom plan view of the base portion, thereof.

1 Claim, 15 Drawing Sheets
